COMBINED CORDLESS BATTERY SHAVER AND HAIR TRIMMER

David Eberhart, Bound Brook, N.J., assignor to Ronson
Corporation, Woodbridge, N.J., a corporation of New
Jersey

Filed May 5, 1966, Ser. No. 2,182

Term of patent 14 years

(Cl. D95—3)

FIG. 1 is a side perspective view of a combined cordless battery shaver and hair trimmer showing my new design.

FIG. 2 is a perspective view of the opposite side of that shown in FIG. 1, the hair trimmer in an upward position.

FIG. 3 is a front view of FIG. 1.

FIG. 4 is a side view of FIG. 1.

FIG. 5 shows the opposite side of FIG. 1.

FIG. 6 is a top view of FIG. 1.

FIG. 7 is a bottom view of FIG. 1.

FIG. 8 is a rear view of FIG. 1.

FIG. 9 is a plan view of the bottom plate thereof taken along the arrow 9 of FIG. 5.

I claim:

The ornamental design for a combined cordless battery shaver and hair trimmer, substantially as shown and described.
